ADVERTISING AND DISPLAY SIGN

John C. Black and Gertrude F. Matthews,
Los Angeles, Calif.

Application April 30, 1932. Serial No. 608,447

7 Claims. (Cl. 40—139)

This invention relates to an advertising and display sign, and particularly to an advertising and display sign capable of being moved or oscillated.

5 The invention is more particularly directed to advertising and display signs to be used in gasoline service stations to advertise gas and oil or other products sold in these stations.

The sign of this invention is based upon the 10 psychological principle that a moving object is more adapted to attract and hold attention than a stationary object. We have, therefore, constructed our sign in such a manner that it may be moved and, preferably oscillated. The motion 15 thus produced is of such a character that the advertisement upon the sign may be easily read or apprehended.

In constructing our sign we prefer to elevate 20 the sign considerably above the ground so that it may be seen at a distance. In doing so, we prefer to use a column or pillar which would harmonize with the architectural features of the station or other building in connection with which the sign is displayed.

25 In constructing the column or pillar, we have avoided the great cost of pillar construction by so constructing the column or pillar which substantially no weight is imposed upon it. This is accomplished in the preferred embodiment by supporting the interior of the column or pillar by an 30 independent structure. In this fashion the outer pillar can be made of a less rigid construction and may, indeed, be merely a false work.

The oscillation of the sign is accomplished by a 35 mechanical motion which will give uniform oscillation in order that the motion will not be jerky, but will be smooth and uniform.

The sign may be constructed in any fashion 40 that may be desired, but we prefer to construct it in the form of a hollow, thin cylinder to provide room for interior illumination; or if high tension gas illuminating signs are employed, such as neon lights, the wiring may be positioned within the cylinder to provide a smooth and uninterrupted 45 exterior.

It is, therefore, an object of our invention to construct an attractive, movable sign upon an attractive support, preferably a pillar or columnar structure.

50 It is a further object of our invention to provide means for moving the sign, preferably an oscillatory movement, whereby said means are hidden within the upright structure and to further provide means whereby the sign may oscillate or move 55 at the top of the pillar or column and to provide

means for sealing the pillar against moisture, rain and dust, while at the same time permitting the motion of said sign. Other objects will appear to those skilled in the art by a study of the herein specification and drawing.

The invention will be more readily understood by reference to the accompanying drawing of which Fig. 1 is a cross section through the column or pillar showing the mechanism. Fig. 2 is a section through the pillar taken at right angles to Fig. 1. Fig. 3 is a section taken at line 3—3 of Fig. 1. Fig. 4 is a fragmentary detail of a section taken along line 4—4 of Fig. 1.

Referring to the drawing: 1 is a pipe firmly fixed in the concrete base 2; 3 is a pillar whose pedestal 4 rests on base 2. The pillar has a capital 5. A door 6 is provided in the pedestal permitting access to the interior of the pillar. Through the lower part of the pipe 1 is passed a pivot pin 7 upon which hang two weights 8 and 9. The weights 8 and 9 carry cross arms 10 and 11. Through the cross arms are passed two pins 12 and 13. The construction of 8 and 9 is such that they have a pendulum motion around pin 7. Through the top of pipe 1 is passed a pin 14 which carries pivoted thereon member 15 carrying arms 16 and 17. Through arms 16 and 17 are passed pins 18. Connecting pins 18 and pins 12 and 13 are connecting rods 19. Positioned upon the member 15 is the cylindrical member 20 capped with plates 21, thus forming a closed cylinder upon which the advertisement may be displayed. Connected to member 15 is a cap in the form of a spherical section 22 composed of flat plates 23 and curved plates 24 which are in the form of an arc struck around point 14. This cap passes through an opening in the capital 5 of the pillar 3. Positioned on the capital 5 are packing plates 26 and 26' which seal the opening 25 through which the cap 22 passes. Motion is imparted by means of a motor 27 positioned on a base 28 within the pillar and operating the mechanism by way of worm 29 and worm gear 30 carried on bracket 31 and oscillating the pendulums 8 and 9 via crank 32.

Referring to the above drawing and description, it will be seen that the whole mechanism is carried upon the pipe 1 and that the pillar 3 carries only its own weight. This permits of a much cheaper construction. The rods 19 are in tension only, and this cheapens the construction as well. The rotation of the motor is transmitted through the worm and worm gear and crank 32, to the pendulums causing them to move uniformly through sections of the arc within the pedestal.

4. It will be seen that in using the worm and worm gear a speed reduction of a desired amount may be obtained. Thus if a motor revolving at 1500 R. P. M. a 100 to 1 worm gear ratio, one 5 very easily obtained, will oscillate the weights 8 and 9 fifteen complete oscillations per minute. This oscillation is imparted by way of rods 19 to the member 15 around pivot 14 and the sign 20 will, therefore, oscillate at the top of the pillar through an arc determined by the crank ratio, slowly and uniformly, approximately, if the above example is followed, fifteen times a minute. This oscillation is sufficiently slow to permit the 10 advertisement on the sign to be apprehended and yet it is sufficiently rapid to attract and hold 15 attention. The motion is uniform and not at all jerky.

Provision is made at the top of the pillar to seal the pillar against dust, moisture and rain. 20 This is provided by means of the cap 22 which, being arcuate in shape at the ends, permits the arcuate ends 24 to pass through the arcuate openings 25. The sides of the cap are, preferably flat and this permits of a sliding seal which will 25 prevent the entrance of moisture and rain. To insure this seal are packing glands 26 and 26', which are so constructed as to be in wiping relation with the exterior of cap 22 and its sides 23 and 24, which positively seals the pillar. Access 30 may be had through the pillar through cap plate 26. A switch 33 and other electrical mechanism may be provided with the pillar.

It will be seen that a very cheap construction is afforded by the above invention and that the 35 pillar can be made cheaply and in conformity with the design and architecture of the structure in connection with which it is used and that a very simple and inexpensive, attractive and striking display sign or advertisement is afforded. 40 The above description is not to be taken as limiting but merely illustrative of our invention which we claim to be:

1. In combination, a hollow pillar, a sign disposed at the top of said pillar and adapted to 45 oscillate thereupon, a support for said sign, a cap plate attached to said sign and passing through the top of said pillar to seal said pillar and to permit the oscillation of said sign, means within the pillar to oscillate said sign.

50 2. In combination, a hollow pillar, a sign disposed on and externally of said pillar, and adapted to oscillate thereupon, means to oscillate said sign disposed within said pillar, connecting

means between said sign and said oscillating means, a cover plate for sealing said pillar against dust and rain, said connecting means passing through said cover plate and said cover plate being attached to said sign, whereby the cover plate seals the pillar throughout the path of motion of said connecting means and said sign.

80 3. In combination, a hollow pillar, a sign movably disposed on and externally of said pillar, means to move said sign disposed within said pillar, connecting means between the sign and said means to move said sign, a cover plate for sealing said pillar against dust and rain, said connecting means passing through the cover means, whereby the pillar is sealed throughout the path of motion of said connecting means.

85 4. In combination, a hollow pillar, a sign disposed on and externally of said pillar and adapted to oscillate thereupon, means for sealing said pillar against dust and rain and adapted to permit oscillation of said sign, means disposed within the pillar for moving said sign, connecting means between said last mentioned means and said sign, said connecting means passing through said sealing means, whereby the oscillating motion is imparted to the sign and whereby said sealing means seals the pillar through the path of motion of said connecting means.

90 5. In combination, a hollow pillar, a sign disposed on and externally of said pillar and adapted to oscillate thereupon, a cover plate for sealing said pillar, said cover plate being attached to said sign to oscillate therewith, means disposed within the pillar to move said sign, connecting means between said sign and said last mentioned means.

95 6. In combination, a hollow pillar, a sign disposed movably on and externally of said pillar, motor means disposed within the pillar to move said sign, means for connecting said sign to said motor means, a cover for sealing said pillar, said cover being attached to said sign to move therewith.

100 7. In combination, a hollow pillar, a sign disposed movably on and externally of said pillar, motor means disposed within the pillar to move said sign, means for connecting said sign to said motor means, a cover for sealing said pillar, said cover being attached to said sign to move therewith, said cover sealing the pillar throughout the path of motion of said sign.
